FIG. 4.

Inventor:

Joseph E. Stagl

UNITED STATES PATENT OFFICE

2,101,761

METATARSAL RUBBER CUSHION REST

Joseph E. Stagl, Brooklyn, N. Y., assignor
to Charles Stagl

Application February 19, 1936, Serial No. 64,769

1 Claim. (Cl. 36—71)

This invention relates to footwear, and its general object is to provide a metatarsal support for a shoe or the like that can be applied in position for use, during or after manufacturing the shoe, and is fixed against casual displacement or removal, for adequately supporting the metatarsal bones, so as to facilitate walking as well as to bring about utmost comfort to the wearer.

A further object is to provide a metatarsal support in the form of a pad of yieldable material, such as rubber or the like, to be secured within a recess in the bottom of the shoe, provided by an opening preferably in the outer and middle sole thereof, so as to be positioned against the insole directly below the intermediate metatarsal bones to cushion the same.

Another object of the invention is to provide a metatarsal support that is simple in construction, inexpensive to manufacture, easy to apply and extremely efficient in use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a side elevation of a shoe with my support secured thereto, and with parts in section to illustrate the arrangement of the support with respect to the soles.

Figure 2 is a bottom plan view showing the support in position for use.

Figure 3 is a top plan view of the support per se.

Figure 4 is a side elevation thereof.

Referring to the drawing in detail, the letter A indicates a shoe that includes the usual outer sole B, an intermediate sole C and an insole D. In preparing the shoe for the application of my support, an opening is provided in the outer and intermediate soles, to provide a recess with its inner end closed by the insole as clearly shown in Figure 1.

The recess is shown as being arranged in the soles at the transverse center thereof and for disposal in a position at the base of the metatarsal bones for a purpose which will be later apparent.

The support is in the form of a pad formed from resilient flexible material such as rubber or the like to provide a substantially flat body 1 of

substantial triangular formation as best shown in Figures 2 and 3, and the body is tapered inwardly from the lower to the upper ends thereof, as best shown in Figure 4.

Formed on and surrounding the body at the lower end thereof is a flange 2, and the bottom or ground engaging portion of the body is rounded outwardly as at 3 or of convexed formation, while the upper surface is likewise rounded outwardly or convexed as at 4.

The body is of a size to snugly fit the recess and is secured therein by any suitable securing means such as cement while the flange is likewise secured to the outer sole, as best shown in Figure 1, which also illustrates that the convexed upper surface of the body raises the insole D above its normal height, and of course the raised portion follows the shape of the convexed upper end, the raised portion being disposed at the base of the metatarsal bones, as will be apparent, with the result the bones are adequately supported, and cushioned to bring about utmost comfort during walking, as well as tending to prevent the formation of calli or the like on the bottom of the foot. Due to the convexed lower or ground engaging surface of the pad, it will be further apparent that smooth rolling action takes place during the walking movement of the wearer, and as the bones are cushioned, the pad facilitates proper walking action and allows the wearer to walk a relatively great distance without tiring or becoming fatigued.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

In a shoe having a recess extending from the insole and through the underside of the outer sole thereof, a metatarsal supporting pad formed from yieldable material to provide a body secured within the recess for disposal at the base of the metatarsal bones, with its outer side exposed to provide a ground engaging or tread surface, said body having a convexed upper surface to raise the insole and a convexed tread surface, and a flange surrounding the body at the tread surface thereof and being secured to the outer sole.

JOSEPH E. STAGL.
